UNITED STATES PATENT OFFICE.

RANDOLPH CROMPTON AND JOHN R. FITTON, OF WORCESTER, MASSACHUSETTS, ASSIGNORS TO RANDOLPH CROMPTON, GEORGE CROMPTON, EDWARD D. THAYER, AND WILLIAM B. SCOFIELD, OF WORCESTER, MASSACHUSETTS.

TAKE-UP MECHANISM FOR LOOMS.

SPECIFICATION forming part of Letters Patent No. 787,281, dated April 11, 1905.

Application filed August 8, 1904. Serial No. 219,857.

To all whom it may concern:

Be it known that we, RANDOLPH CROMPTON and JOHN R. FITTON, citizens of the United States, residing at Worcester, county of 5 Worcester, and State of Massachusetts, have invented an Improvement in Take-Up Mechanism for Looms, of which the following description, in connection with the accompanying drawings, is a specification, like characters on the drawings representing like parts.

This invention relates to that class of loom take-up employing a worm and worm-wheel for turning automatically the sand-roll or other parts for winding the cloth as it is woven, 15 the object of our invention being to suspend at will the operation of the automatic means that the sand-rolls may be turned freely while the worm and worm-wheel remain at rest, such provision saving very much valuable 20 time of the weaver.

Figure 1 in end elevation shows a loom provided with take-up mechanism embodying the invention to be herein claimed. Fig. 2 is a partial front end view of the loom, Fig. 1, with the 25 worm-shaft and the clutch-controlling shaft in section. Fig. 3 is a partial section taken through gear 4 on the sand-roller and gears 2 and 3. Fig. 4 is a section on the line $x-x'$, Fig. 3, and Fig. 5 is a section on the line $x''-x''$, Fig. 3.

Referring to the drawings, A represents the end frame of a loom, B the usual breast-beam, C the usual take-up or sandroller, D a cloth-guiding roller, E the cloth-receiving roller, and F the cam-shaft, which parts may be all 35 as common in looms.

The shaft F has applied to its end a bevel-gear a' , that engages a pinion a'' , mounted loosely on the end of a worm-shaft a^2 , held in suitable bearings a^3 a^{3x} , sustained by the loom side. 40 One end of the bevel-pinion a' has a series of teeth a^4 , that may be engaged by a series of teeth b of a collar b' , connected with the worm-shaft a^2 by a spline, so that said collar may be moved when desired longitudinally of the 45 shaft a^2 to cause the teeth of the collar to be

disengaged from the teeth of the continuously-rotating bevel-pinion a' when it is desired to stop the rotation of the worm-shaft a^2 , it being understood that when said collar and said worm-shaft are uncoupled the shaft remains 50 at rest.

To control the collar b' and cause it to be disengaged from the continuously-rotating bevel-pinion a' or to be engaged therewith, the collar is shown as provided with an annular groove g , that is entered by the forked end of a lever c , pivoted at g' on an ear of the bearing a^3 , said lever having connected with it at g'' between its ends a rod c' , that is extended through a hole in the bearing a^{3x} and provided beyond said bearing with a collar h^w , fixed thereto, said collar being acted upon when desired by the lower end of a hand-lever d , secured to the end d' of the usual shipper-rod, extended through the loom side. The 55 shipper-rod is surrounded at the right-hand side of the bearing a^{3x} by a spring h^{wx} and an adjustable collar h^{wz} , the spring abutting one side of the collar and the bearing, so that said spring acts normally to effect the engagement 60 of the collar b' with the teeth of the pinion a' and rotate the shaft a^2 , provided with a worm c , that engages the teeth of a worm toothed wheel a' , secured to a shaft e^2 , extending through the loom side, as shown, and provided with a gear 1, that engages a pinion 2, having affixed to one side of it a smaller pinion 3, that in turn engages the teeth of a toothed wheel 4, fast on the axis or the journal of the sand-roller. The toothed wheel 4 70 75 80 85 90

engages a pinion 5, that engages a pinion 6, that in turn engages a pinion 7, mounted on the shaft 8, the latter when rotated turning the cloth-receiving roller E.

The outer end of the worm-shaft a^2 is provided with a hand-wheel f' , having a pivoted handle or crank f'' . When the loom is running and weaving is going on, the hand-lever d occupies its dotted-line position, Fig. 1, and the collar b' engages the teeth of the continu-

ously-rotating bevel-pinion a' , and the worm-shaft and worm rotate the worm-wheel e' automatically. Whenever an imperfect spot or fault in the cloth is discovered, the sand-roller 5 and cloth-receiving roller must be turned backwardly, and the weft inserted in the warp is pulled out until perfect cloth is reached. It has been customary prior to our invention to disconnect the worm e from the worm-shaft 10 and through a hand-wheel turn the worm backwardly to thus turn the worm-wheel and gearing actuated thereby backwardly and also turn backwardly the sand-roller and unwind the cloth-receiving roll. When the worm e is employed to turn the worm-wheel, sand-roller, and other parts backwardly, a very considerable amount of time is necessary, and to expedite the turning backwardly of the sand-roller and cloth-receiving roller we have 15 mounted the pinion 2 loosely on a stud h of a bracket h' , held on a stand h^2 , fast to the loom-frame, and have provided the side of said pinion with a space to receive the end of a toothed sleeve h^3 , that is surrounded by the small pinion 3, the latter and the sleeve being connected by a spline. (Shown best in Fig. 3.)

The stud h has an annular groove that is entered by a pin 10, extended through a hole in the sleeve and connected with a spring 12, fast 30 at one end of the sleeve. When it is desired to disconnect the train of driving mechanism between the sand-roller and the cloth-receiving roller, so that the sand-roller may be turned backwardly without turning the worm-wheel or the worm, it is only necessary to withdraw the pin 10 from the annular groove in the stud and engage the sleeve by its end and pull the same outwardly or to the left, Fig. 3, until the inner end of the sleeve is 35 withdrawn from the opening referred to in the side of the pinion 2. This done, the hand-wheel m of the sand-roller may be engaged by the hand and the latter turned backwardly, causing its toothed wheel 4 in engagement 40 with pinion 3, then loose on the stud, to be rotated freely while the worm-wheel and worm remain at rest, and at the same time the cloth-receiving roller will be turned in the corresponding direction through the pinions 5, 6, 45 and 7, actuated by the gear 4.

We are not aware that prior to our invention intermediate gearing between the toothed wheel on the sand-roller and the usual worm-wheel actuated by the worm on the loom-shaft 55 has ever been so constructed as to be disengaged to run freely while the sand-roller is turned by hand. By this improvement very much time of the operator may be saved.

To suspend the operation of the worm-shaft 60 a^2 preparatory to turning the sand-roller backward or the take-up roller or the cloth-receiving roller backward, it is only necessary to move the hand-lever d from its dotted-line position into its full-line position, causing its

end to act on the collar h^{10} and compress the spring h^{12} , thus moving the lever c to effect the unclutching of the collar b' from the teeth of the continuously-moving bevel-pinion a' .

Prior to this invention it had been customary to mount a worm used to rotate the worm-wheel of the take-up mechanism on the sleeve capable of being temporarily disconnected from the shaft used to turn the worm for actuating the sand-roller when the cloth was to be run over the same backwardly to correct a fault in weaving, and to do this the sleeve and worm had to be turned by the hand of the operator, as stated, and this process is so very slow that the operator is tempted to keep on weaving, notwithstanding the fault in the cloth, rather than lose the time necessary to correct the fault. In our invention by simply disconnecting and leaving loose an intermediate pinion in the train of gearing between the usual worm-wheel and the toothed wheel 85 on the sand-roller the latter is left entirely free to be turned readily by hand to give up its imperfect cloth to be corrected by the weaver.

Having fully described our invention, what we claim as new, and desire to secure by Letters Patent, is—

1. The combination with a worm-wheel forming a part of a train of take-up mechanism, and a continuously-rotating gear a , of a worm-shaft having a worm, a toothed collar splined on said worm-shaft, and a bevel-pinion having teeth at one end and mounted loosely on said shaft, said bevel-pinion being adapted to be rotated continuously by said gear, a rod 100 extended in the same direction as said shaft, and means operative on the stopping of the loom to move said rod and effect the disengagement of said collar and bevel-pinion when it is desired to stop the worm-shaft and suspend the operation of the take-up mechanism.

2. In a take-up mechanism, the combination with a worm and worm-wheel, a sand-roller having an attached toothed wheel, and a driving-train intermediate the shaft of said worm-wheel and the wheel of the sand-roller, of means for disconnecting and leaving loose one of the intermediate pinions of said driving-train that the sand-roller may be turned freely while the worm-wheel and worm remain at rest.

3. In take-up mechanism for looms, the combination with a worm-wheel, its shaft, and a gear connected therewith, and a sand-roller having a connected toothed wheel, of a pinion meshing with the gear carried by the shaft of the worm-wheel, a pinion meshing with the toothed wheel carried by the sand-roller and means for temporarily disconnecting said pinions that the sand-roller may be turned by hand and leave the worm-wheel and its shaft at rest.

4. In a take-up mechanism for looms, a

take-up roller, a worm-shaft and an intermediate shaft for driving said take-up, means for driving said worm-shaft, and automatically-controlled means to stop the rotation of said worm-shaft whenever the shipper is moved.

In testimony whereof we have signed our

names to this specification in the presence of two subscribing witnesses.
